UNITED STATES PATENT OFFICE

CHARLES E. GRIFFITH, OF PHILADELPHIA, PENNSYLVANIA.

CAR VESTIBULE-DOOR AND TRAP.

No. 876,871.

Specification of Letters Patent.

Patented Jan. 14, 1908.

Application filed August 20, 1907. Serial No. 889,887.

To all whom it may concern:

Be it known that I, CHARLES E. GRIFFITH, a citizen of the United States, residing at Philadelphia, in the county of Philadelphia and State of Pennsylvania, have invented new and useful Improvements in Car Vestibule-Doors and Traps, of which the following is a specification.

This invention relates to car vestibule doors and traps, the object of the invention being to provide an effective device of this character involving means for opening the vestibule door with ease, the said means being of such character as to not interfere in any respect with the departure of a passenger from or his entrance into the car.

The invention includes other advantageous features which with the foregoing will be set forth at length in the following description wherein is outlined that form of embodiment of the invention which I have selected for illustration in the drawings accompanying and forming part of this specification.

Referring to said drawings: Figure 1 is a longitudinal sectional view of the end of a car equipped with a vestibule and trap involving my invention. Fig. 2 is a horizontal sectional view of the same. Fig. 3 is a transverse section on the line 3—3 of Fig. 2. Fig. 4 is a detail in perspective on an enlarged scale of the trap-operating mechanism, and Fig. 5 is a similar view of a hinge member.

Like characters refer to like parts throughout the several figures of the drawings.

In the drawings I have shown part of an ordinary car, the same being designated by 2 and having in one end, as indicated in Fig. 3, a door-opening as 3 for the entrance of passengers into the car or their departure therefrom. The car also involves the customary platform 4 from which the steps 5 (see Fig. 3 for example) lead. A trap such as that denoted in a general way by 6 is adapted to cover or extend across the steps when in its closed position at which time it is in line with and constitutes in effect a lateral extension of the platform, as shown clearly in Fig. 3. The usual vestibule portion of the car is designated by 7 and it has a side opening as 8 in which the vestibule door 9 is adapted to fit when closed, the door being hinged to the car in the customary manner and being adapted to swing toward the end thereof on its opening movement.

The trap 6 is shown as being substantially

square in form and as consisting of two duplicate sections 10 and 11, the section 10 being hinged to one end of the car 2 in any desirable way, and the section 11 being hinged to the door 9. The two sections of said trap are in turn hinged to each other and along a line diagonally or obliquely disposed with respect to said trap. When the trap is closed the two sections are in horizontal alinement, the door 9 being at this time shut or occupying the opening 8. Owing to the exact alinement of the said sections 10 and 11 it is necessary to forcibly break the joint between the same to effect the opening of the door 9. After the said joint is broken it becomes an easy matter to swing the door 9 open by directly engaging the same. I will hereinafter describe the means shown for breaking this joint.

The trap 6 is connected, as will be clear, both with the car 2 and the vestibule door 9. There is a novel form of hinge connection between the trap 11 and the door 9 and I will now describe the same. To the inner face of said door at a place near the lower end thereof is connected in some suitable way, as by screws for example, the plate 12. This plate constitutes one member or leaf of a hinge, the other member of the hinge being designated by 13 and consisting of an angular arm fitting around the outer side of said trap 6 adjacent to the door 9, as clearly indicated in Fig. 3. The hinge member or leaf 13 may be fastened to the trap section 11 in any desirable way and its upwardly-extending vertical branch is provided with an eye as 14 through which the rod 15 passes, said rod being also seated in perforations or seats in the vertically-adjustable blocks or boxes 16 and being rigidly connected therewith in any desirable way. The eye or loop 14 in the present case has a sliding movement on the rod 15. The hinge member or leaf 12 is connected fixedly with the inner face of the vestibule door 9 at a point somewhat remote from the hinge. The trap 6, it will be clear, has a vertically-adjustable hinge connection with the vestibule door 9 so that, notwithstanding the fact that the latter may sag, the trap 6 can always be maintained in a true horizontal position by vertically adjusting one or both of the blocks or boxes 16. By virtue of this feature canting of the said trap can be avoided. The blocks or boxes 16

16 are vertically slideable between the outwardly converging side walls of upper open-ended slots as 17 extending in parallelism downwardly from the upper edge of the hinge-member or plate 12. To said blocks or boxes are swiveled the adjusting screws 18 which are tapped through lugs or ears as 19 projecting from said member or plate 12. The lower ends of these adjusting screws are 10 squared or otherwise suitably shaped to receive a wrench, by turning which the blocks 16 can be raised or lowered. The screws at opposite sides of the lugs 19 are provided with jam-nuts as 20, serving their usual function.

To the timber 21 which extends longitudinally of the car below the platform 4 is attached in some suitable manner the depending bracket 22 to which the angle of an angle lever as 23 is pivoted or otherwise fulcrumed, the longer upper arm of the angle lever extending rearward and upward at an inclination and having a bifurcated portion as 24 straddling the lower end of the depressing rod 25, said rod having pins as 26 near its lower end, which enter slots in the branches of said bifurcated portion 24, as indicated clearly in Fig. 4. There is therefore a loose connection between the lower end of the rod or spindle 25 and the long arm of the angle lever 23. The rod 25 extends through the platform 4 and its upper end is provided with a head or knob as 27 which can be engaged by the foot or hand 30 to facilitate the depression of said rod. The lower and shorter arm of the angle lever 23 is pivoted or otherwise flexibly connected with the forward end of connecting bar 28, while the rear end thereof is likewise connected to a lever such as that denoted in a general way by 29 and which in the present case, in order to insure compactness, which is a consideration of some importance, is located substantially directly under the rod or spindle 25. The lever 29 consists of an upper portion as 30, a transversely disposed horizontal portion as 31, and a lower portion as 32 and is generally made in one piece. The horizontally-disposed transverse portion 31 40 is located under the timber 21, the upper portion 30 of the lever being located approximately at one side of said timber, while the portion 32 of said lever is located approximately at the opposite side of said timber. 50 The pivot for the lever 30 is situated near the upper end thereof and consists of a pin as 33 sustained by the timber 21 and it also serves as a center for the lever 34, the curved inner portion of which bears against the laterally-disposed lug or projection 35 at the upper end of said lever 30, as clearly shown in Fig. 4. The lever 34 has at its outer end a projection or fin as 36 adapted to slide in the longitudinal slot 37 of the 55 plate or bar 38 suitably attached to the inner

edge of the obliquely-divided trap 6 and extending from the inner end to the outer end thereof.

The normal positions of the parts are shown in Figs. 1, 2, and 3 of the drawings, the trap 6 and vestibule door 9 being closed, the sections of the trap being in exact horizontal alinement. To break the joint between the said trap sections to thereby effect the easy opening of the vestibule door 9, the rod 25 is thrust downward by foot or hand. As said rod 25 moves downward the upper and long arm of the angle lever 23 is moved in a corresponding direction so as to swing the other arm of said angle lever to the right in Fig. 1, 75 the angle lever on such movement pulling the bar 28 to the right and moving the lower long branch of the lever 29 in a corresponding direction, the short upper branch of said lever 29 being swung to the left and the lug or projection 35 thereon serving to lift the lever 34 which lifts the section 10 of the trap and thereby breaks the joint between said section and the corresponding section 11, so that the opening movement of the door can be started, following which the full opening movement of the door can be easily effected. Owing to the construction and arrangement of the several levers I initially apply to the said trap a powerful leverage which insures the ready and easy elevation of the same and the consequent initial opening of the door 9. At this point it is an easy matter to fully swing the door 9 open; and as it does open, the sections 10 and 11 are upwardly folded 85 and the section 11 will lie against the section 10 in the space between the door 9 and car 2 when said door 9 is open. Owing to the fact that the rod 25 is next the car 2 and is at one side of the opening 3, said rod does not affect 95 in anywise the entrance of passengers into or their departure from the car; in other words, such persons will not trip on the rod in entering or leaving the vestibule of the car or in passing from one car to another. By a slow 100 downward movement of the rod 25 a slight opening of the door 9 can take place by the breaking of the joint between the sections 10 and 11, whereby said door can be swung open by hand. By a forcible downward movement of the rod, the door 9 can be thrown wide open through the medium of the trap and can be held in such relation by a snap or other device suitably placed on the body of the car.

What I claim is:

1. The combination in a car of a vestibule door and a trap, said trap being hinged to the car and also having a vertically adjustable hinged connection with the door.

2. The combination in a car of a vestibule door and a trap hinged to the car and comprising flexibly connected sections, one of which is connected with said door by a vertically adjustable hinged connection.

3. The combination in a car of a vestibule door, a trap when closed to cover the steps of said car, a hinge member connected with the trap, a hinge member fastened to the door and comprising vertically adjustable blocks, and a rod carried by said blocks and to which said first mentioned hinge member is connected.

4. The combination in a car of a vestibule door and a trap, said trap comprising two sections hinged to each other along a line extending obliquely thereof, the sections of the

trap being united with the car and vestibule door respectively by hinged connections, and one of said hinged connections being vertically adjustable. 15

In testimony whereof I have hereunto set my hand in presence of two subscribing witnesses.

CHARLES E. GRIFFITH.
